[57] CLAIM

The ornamental design for a plant stand, as shown and described.

DESCRIPTION

FIG. 1 is a perspective view showing my new design;
FIG. 2 is a side elevation view thereof as viewed from
the right in FIG. 1;
FIG. 3 is a side elevational view thereof as viewed from
the left in FIG. 1;

FIG. 4 is a rear side elevational view thereof;

FIG. 5 is a top plan view thereof; and,

FIG. 6 is a bottom plan view thereof.

The characteristic feature of the plant stand resides in
the overall design, especially the shape of the base sup-
port and the arm supports.
